UNITED STATES PATENT OFFICE.

BARNET L. STEIN, OF GLENCOE, AND FRANK KAPLAN, OF EVANSTON, ILLINOIS.

DESIGN FOR A SCENIC SETTING FOR STORE DISPLAY.

Application filed July 30, 1927. Serial No. 22,965. Term of patent 14 years.

To all whom it may concern:

Be it known that we, BARNET L. STEIN and FRANK KAPLAN, citizens of the United States, residing, respectively, at Glencoe and Evanston, in the county of Cook and State of Illinois, have invented a new, original, and ornamental Design for Scenic Setting for Store Display, of which the following is a specification, reference being had to the accompanying drawing, forming a part thereof.

We claim:

The ornamental design for a scenic setting for store display, as shown.

BARNET L. STEIN.
FRANK KAPLAN.
